DESIGN FOR A DISPLAY BASKET

James Doig, Wilmette, Ill., assignor to The Niagara Lithograph Company, Buffalo, N. Y., a corporation of New York

Application March 25, 1937, Serial No. 68,399

Term of patent 7 years

To all whom it may concern:

Be it known that I, James Doig, a citizen of the United States, residing at Wilmette, in the county of Cook and State of Illinois, have invented a new, original, and ornamental Design for a Display Basket, of which the following is a specification; reference being had to the accompanying drawing, forming a part thereof.

In the drawing:

Fig. 1 is a perspective view of the display basket, showing my new design;

Fig. 2 is a plan view; and

Fig. 3 is an end view.

I claim:

The ornamental design for a display basket, substantially as shown.

JAMES DOIG.
